UNITED STATES PATENT OFFICE.

WILLIAM COOPER, WILLIAM H. WARREN, AND CHARLES A. MUDGE, OF CINCINNATI, OHIO, ASSIGNORS TO THE BULLOCK ELECTRIC MANUFACTURING COMPANY, OF SAME PLACE.

BRUSH-HOLDER FOR COMMUTATORS.

SPECIFICATION forming part of Letters Patent No. 634,804, dated October 10, 1899.

Application filed May 18, 1898, Serial No. 681,009. (No model.)

To all whom it may concern.

Be it known that we, WILLIAM COOPER, WILLIAM H. WARREN, and CHARLES A. MUDGE, citizens of the United States, and 5 residents of Cincinnati, in the county of Hamilton and State of Ohio, have invented certain new and useful Improvements in Brush-Holders for Electric Commutators, of which the following is a full, clear, and exact description, 10 reference being had to the accompanying drawings, forming part of this specification.

Our invention relates to an improvement in brush-holders for electric commutators, its object being to construct a brush-holder 15 for carbon or any non-metallic electrical conductors and at the same time operative with a metallic electrical conductor. It is to provide a simple holder easily accessible for the purpose of removing or changing the brush 20 and adjustable for regulating the pressure and also the angle of contact between the brush and the commutator.

The invention, with certain mechanical modifications, is illustrated in the accompanying 25 drawings.

Figure 1 is a rear elevation of the holder when the hinged arm is made bifurcated. Fig. 2 is a vertical cross-section of the same. Fig. 3 is a rear elevation of the bifurcated 30 swinging arm. Fig. 4 is a side elevation of the same. Fig. 5 is a side elevation of the thumb-piece by which the end of the spring is held to the arm and its tension changed. Fig. 6 is an elevation of the same.

35 Like letters of reference indicate identical parts in all the figures.

A is the commutator, and B the brush, which consists of a block of electrical conducting material, such as carbon or copper, and we 40 prefer to have its opposite ends beveled toward each other, though the end away from the commutator may be merely notched to receive the end of the swinging arm C. A casting D is journaled on a suitable bearing passing through the opening D' and forms, prop-

erly speaking, the seat for the block of carbon B. This block of carbon, resting upon the smooth flat surface B', is slidable over this surface. The holder is provided with a set-screw F, by which the angle of the flat 50 seat B' may be changed and adjusted with relation to the commutator. The face of this flat seat B' extends to within a short distance of the face of the commutator, the carbon or brush B resting upon it and extending beyond it against the face of the commutator. 55 We prefer to place the holder so that the extreme end of the seat B' will be below the plane passing through the axis of the commutator and the angle at which this seat is 60 placed, such that pressure of the commutator upon the carbon will tend to hold it down upon its seat no matter which way the commutator is revolving.

To the lower end of the casting or holder 65 is journaled a curved bifurcated arm C, the lower end being journaled at c and the upper end curved round, so that it may press against the outer end of the brush B. To hold this arm C against this brush, we provide the 70 coiled spring E. One end of this spring is fixed to the holder at E'. The opposite end is attached to the swinging curved arm C by the thumb-piece P. This thumb-piece P is held between the bifurcations of arm C by 75 detents or pawls p' on the thumb-piece, which take into notches p of the arm C, and the thumb-piece is held in place by the tension or pulling of spring E. By pulling on the thumb-piece P and disengaging the pawls 80 p' from the notches p the thumb-piece can be applied at different distances from the pivotal point of the arm, and thus the pressure of the arm on the carbon varied.

Having thus described our invention, what 85 we claim, and desire to secure by Letters Patent, is—

The combination with a commutator, of a block of carbon or other electrical conductor, one of its beveled ends lying against the 90

commutator, a flat and adjustable conducting-plate upon which the block rests and is movable, a pivoted bifurcated arm whose free end bears against the other end of the brush, and provided with notches in its bifurcations, a thumb-piece provided with pawls which engage in said notches, and a coiled spring whose normal tendency is to hold said thumb-piece in contact with the arm and one

end of the arm against the brush, substantially as and in the manner described.

WILLIAM COOPER.
WILLIAM H. WARREN.
CHARLES A. MUDGE.
